UNITED STATES PATENT OFFICE.

WILLIAM H. BRYANT, OF BOSTON, MASSACHUSETTS, ASSIGNOR TO FREEMAN HUNT, TRUSTEE, OF CAMBRIDGE, MASSACHUSETTS.

AMUSEMENT APPARATUS.

No. 884,462.

Specification of Letters Patent.

Patented April 14, 1908.

Application filed May 17, 1907, Serial No. 374,134. Renewed February 19, 1908. Serial No. 416,778.

To all whom it may concern:

Be it known that I, WILLIAM H. BRYANT, a citizen of the United States, residing at Boston, in the county of Suffolk, State of 5 Massachusetts, have invented a certain new and useful Improvement in Amusement Apparatus, of which the following is a specification, reference being had therein to the accompanying drawings.

10 The invention consists in certain improvements in amusement apparatus of the general class in which a base-ball or the like is thrown at a mark from a short distance.

Broadly stated, the invention consists in 15 an amusement apparatus of the class above referred to, comprising, in combination, a mark at which a base-ball is to be thrown or hurled, an interference device or "interference" located in advance of the said mark, 20 and means to produce relative reciprocation of the said mark and interference in a direction intersecting the path of flight of the said base-ball, to cause one of such parts to pass into and out of line with the other there- 25 of with frequency. During the brief inter-

val while the mark and interference remain in line with each other the interference "covers" or shields the mark so as to block or divert a base-ball proceeding directly to 30 ward the mark. It is possible to land the base-ball against or within the mark only when the former is thrown so that it approaches the latter at a moment when the mark and interference are disaligned with each 35 other.

The invention is shown herein embodied in two figures which are made up to resemble base-ball players, one representing a batter and one a catcher, the batter holding in its 40 hands a bat, extended, constituting the interference device or "interference"; and the catcher being in place behind the bat, with hands gloved and properly disposed for catching a ball which passes the bat, such 45 hands constituting the mark at which the ball is thrown. The bat is shown as having combined therewith mechanism by which it is swung up and down automatically in front of the catcher's hands so that at short intervals of time, while passing the position of the 50 said hands, it momentarily shall be capable of blocking the entrance into the concavity thereof of a ball thrown at such concavity. The hands of the catcher, also, have com-

bined therewith mechanism by which they 55 are moved automatically so as to continuously shift their position up and down. Thereby the undertaking to hit the catcher's hands by a thrown ball which shall pass clear of the moving bat is rendered more complicated, and the difficulty of succeeding is increased.

In the drawings,—Figure 1 shows the figures aforesaid in elevation. Fig. 2 shows the batter in section in horizontal plane 65 passing approximately through the elbow-joint, the bat being partly broken away. Fig. 3 shows a portion of the batter in vertical section and with the spring drum partly broken away. Fig. 4 is a view of the motor 70 mechanism of the batter, showing the side thereof which is opposite that represented in Fig. 3. Fig. 5 shows in plan the catcher's hands, and a mechanical sounding device applied thereto and adapted to be operated 75 by a ball striking fairly within the said hands. Fig. 6 is a diagram of an electrical arrangement for sounding a bell when the ball strikes properly.

In the drawings,—A designates the figure 80 of the batter, and B is the bat held by the hands C, C, of the said figure. D is the figure of the catcher, and E, E, are the gloved hands of the latter figure. The fore-arms F, F, of the batter are connected movably 85 with the remainder of the figure, so as to enable them to swing up and down with the bat. For the actuation of the bat, a rock-shaft, 1, Figs. 2, 3, and 4, is provided. This rockshaft extends from one side of the body 90 of the batter to the other, that is to say in the direction from front to rear in Fig. 1 of the drawings, its axis being located in line with the elbow-portion of the arm which is fully exposed to view in Fig. 1. Upon the opposite ends of this rockshaft are mounted and fixed the arms 2, 2, Fig. 2, which extend in the same direction as the fore-arms F, F, and have the latter connected with or built upon the same. The arms 2, 2, converge toward 95 each other, and the converging ends thereof receive between them the handle-end of the bat B, the said ends and the bat being secured together by bolts 3, 3, and nuts 4, 4, so as to hold the bat firmly. A cross-tie or 100 brace, 5, placed between the converging portions of the arms 2, 2, and having its opposite ends secured to the said arms by bolts

6, 6, and nuts or taps 7, 7, joins the arms together intermediate the bat and the rock-shaft so as to give greater strength and enable the bat and its carrying means to withstand to greater advantage the effects of blows of balls against the free end of the bat.

With the rockshaft 1 I combine a counter-balance, 8, Figs. 2 and 3, for the arms 2, 2, forearms F, F, and bat B, and I also combine with it means by which it automatically is rocked so as to produce the required movement of the bat. The means just mentioned comprises, in the drawings, a rotating crank, 9, Fig. 4, which is connected by a link, 10, to an arm 11 fixed upon the said rockshaft, and a spring motor, shown in Figs. 3 and 4, which is connected by gearing with the said crank. By the rotation of the crank occasioned by the spring motor, the required rocking movement of the rockshaft is produced.

The crank 9 is in gear-connection with the spring-motor by means of a spur-pinion 12, Fig. 4, which is fixed to the crank, and a spur-gear 13 with which the pinion 12 engages, the said gear 13 being fixedly connected with the drum 14, of the spring motor, and the said drum and gear being mounted upon a supporting shaft 15 with capacity to turn independently with relation thereto. Within the drum 14 is contained the spring 16, Fig. 3, one end of which is made fast to the drum and the other end thereof to the said supporting shaft 15. For the purpose of enabling the spring to be wound up, the shaft 15 has fixed thereon a spur-gear 17, Fig. 3, with which meshes a spur-pinion 18, on a winding shaft 19, the outer end of which projects to the exterior of figure A at an accessible point and is squared to receive a suitable key, 20, shown by dotted lines in Fig. 1. To prevent retrograde turning of the shaft 15 after the spring has been wound up by the means just explained, a ratchet or detent wheel 21, Fig. 3, is fixed upon shaft 15, and a weighted pawl 22, for engaging automatically with the teeth of the said wheel, is pivoted upon an adjacent fixed part of the supporting stand or framework. As the drum 14 is turned by the action of the spring, rotary movement is transmitted therefrom to the crank 9 through the gearing 13, 12. For the regulation of the rate of rotation of the crank 9, and consequently of the frequency, etc., of the swinging movements of the bat B, a governor or fly is provided at 23, Figs. 3 and 4, it being in gear-connection with crank 9 through gearing 24, 25, 25, 26, Fig. 4, the spur-pinion 24 being fast on the shaft of the governor or fly 23, and the spur-gear 26 being fast with the crank, the said spur-pinion and spur-gear being connected through the intervening gears 25, 25, etc. The said governor or fly may be, in practice, of any approved character and construction.

The arms H, H, of the catcher are mounted

and actuated substantially as in the case of those of the batter, portions of the supporting arms 2^a 2^a thereof being shown in Fig. 5, the construction, connections, and actuating spring motor being essentially the same as those already described. These features are unnecessary to be shown and described in detail. The winding-shaft, 27, of the spring-motor of the catcher is indicated in Fig. 1.

In practice, the movable parts of both figures may be made to operate, but so as to cause the bat and the catcher's hands to move always oppositely with reference to each other. Or the relative speeds may be varied, so that the bat shall move more rapidly than the catcher's hands, or, vice versa. Or the bat may be caused to move while the catcher's hands stand still, or vice versa.

For the purpose of announcing or signaling the fact when a base-ball lands against or within the mark, *i. e.* in the present instance the catcher's hands, I combine with the latter either a mechanical device as in Fig. 5, or an electrical arrangement as in Fig. 6. Thus, in Fig. 5, a movable plate 28 is located within the concavity of the hands E, E. This plate extends across the rear portion of the said concavity, and a base-ball which passes fairly into the concavity will make impact against the plate. The plate is furnished with a rearwardly projecting stem or spindle 29, which works in a guide 30 that is supported by or in connection with the hands E, E, at or adjacent the wrists. Within this guide is an expanding spiral spring, 31, which is compressed between a collar at the rear end of the guide and a shoulder on the forward portion of the spindle. By the expansion of the spring, the spindle and plate are held in an advanced position, with a stop-collar 32, that is fixed upon the rear portion of the spindle, in contact with the rear end of guide 30. The blow of the base-ball upon the front face of plate 28 drives back the latter and spindle 29, overcoming the resistance of the spring 31, after which the spring, in expanding, moves the spindle and plate forward again. At 33 is the shell of a gong, at 34 the clapper or hammer thereof, hung or pivoted to the fixed support 35, and at 36 is the retracting spring for the said clapper or hammer. When the plate 28 is driven back by the impact of the base-ball, the rear end of spindle 29 by acting against the clapper or hammer 34 throws the latter so as to cause it to strike the shell 33, causing the latter to sound. In Fig. 6, at 37 is shown a movable electrical contact or terminal arranged to be operated by the plate 28 when the latter is driven back by the impact of a base-ball. The said contact is connected by a conducting wire 38 with an electro-magnet 39, from which a wire 40 extends to one pole of a 135

battery 41. At 42 is a fixed contact or terminal against which the movable contact or terminal 37 is carried by rearward movement of plate 28. Contact or terminal 42 is connected with the other pole of the battery 41 by wire 43. When movable contact or terminal 37 is caused to touch fixed contact or terminal 42, the circuit is completed to and through the electro-magnet 39, and the latter, becoming excited, acts upon an armature lever 44 to move the latter. The movement of the said armature lever is made instrumental in causing an electric bell or buzzer to sound. Thus, from the said lever a wire extends to one binding post of the bell 47, and from the other binding post of the latter a wire 48 extends to and connects with the wire 43. At 50 is a wire connecting with the wire 40 and extending to the fixed contact 49. The movement of the armature lever aforesaid causes it to touch fixed contact 49, thereby closing the circuit from the battery through the bell. In order to prolong the ringing of the bell, a dash-pot, 51, of well-known type is combined with the armature lever 44, this dash-pot acting to retard the return movement of the armature lever under the action of spring 52 after the contacts at 37, 42, have separated and the excitation of the electro-magnet 39 has ceased, and thus prolong the period of the engagement of the said armature-lever with the fixed contact 49.

While I have been careful to describe fully the illustrated embodiment of the invention, it is to be understood that the details of construction, etc., may be varied in many respects without involving any departure from the invention. The particular means and manner of supporting and actuating the bat and catcher's hands, and the character of the device for announcing or signaling that the thrown ball has landed upon the desired mark, are not in themselves of the gist of the invention. The motor employed need not necessarily be a spring motor, for other known motive mechanisms may be used in lieu thereof if found desirable.

While the invention is shown and described herein as embodied in connection with figures representing a base-ball batter and catcher, the invention is not necessarily restricted in all its phases to an amusement apparatus in which the mark thrown at is the hands of a base-ball catcher, and the interference device is a base-ball bat, for the mark and the interference device or "interference" may be varied more or less in design.

I claim as my invention:—

60 1. In an amusement apparatus, in com-

bination, a mark for a missile, an interference in advance of the said mark, and means to produce relative reciprocation of the said parts in a direction intersecting the path of flight of the said missile to cause one 65 thereof to pass into and out of line with the other with frequency.

2. In an amusement apparatus, in combination, the baseball catcher and its hands, the base-ball batter holding a bat adapted to 70 constitute an interference in the path of flight of a base-ball thrown at such hands, and means to produce relative reciprocation of said hands and bat in a direction intersecting the said path to cause one thereof to 75 pass into and out of line with the other thereof.

3. In an amusement apparatus, in combination, the baseball catcher having hands disposed to catch a ball, the baseball batter 80 holding a bat adapted to constitute an interference in the path of a ball thrown toward the said catcher's hands, and means to reciprocate the said hands and the bat, respectively, in a direction intersecting the said 85 path.

4. In an amusement apparatus, in combination, the baseball catcher having hands disposed in position to catch a ball, the base-ball batter holding a bat adapted to constitute 90 an interference in the path of a ball thrown toward the said catcher's hands, and means for independently reciprocating the catcher's hands and the bat, respectively, with relation to the said path. 95

5. In an amusement apparatus, in combination, the base-ball catcher having hands in position for catching a ball, the base-ball batter holding a bat adapted to constitute an interference in the path of a ball thrown toward the said hands, means to produce relative reciprocation of said hands and bat in a direction intersecting the said path, and a signal for announcing the striking of the said hands by a thrown ball. 100

6. In an amusement apparatus, in combination, a mark having a concavity to be entered by a base-ball which is thrown at such mark, an interference device in advance of the said mark, and means to produce relative reciprocation of the said parts in a direction intersecting the path of flight of the said base-ball to cause one thereof to pass into and out of line with frequency. 105

In testimony whereof I affix my signature 110 in presence of two witnesses.

WILLIAM H. BRYANT.
